US0D1061836S

(12) **United States Design Patent** (10) **Patent No.:** **US D1,061,836 S**
(45) **Date of Patent:** **** Feb. 11, 2025**

(54) **PORTABLE AIR CONDITIONER**

(71) Applicant: **Weiquan Zou**, Loudi (CN)

(72) Inventor: **Weiquan Zou**, Loudi (CN)

(**) Term: **15 Years**

(21) Appl. No.: **29/910,538**

(22) Filed: **Aug. 21, 2023**

(30) **Foreign Application Priority Data**

Jul. 27, 2023 (CN) 202330473238.6

(51) **LOC (15) Cl.** **23-04**

(52) **U.S. Cl.**

USPC **D23/333**

(58) **Field of Classification Search**

USPC D23/328, 332, 333, 335, 336, 355, 371,
D23/370

CPC F24F 13/082; F24F 13/28

See application file for complete search history.

(57) **CLAIM**

The ornamental design for a portable air conditioner as shown and described.

DESCRIPTION

FIG. 1 is a perspective view of a portable air conditioner showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is an enlarged view of portion 9 shown in FIG. 1. The dash-dash broken lines in the drawings depict portions of the portable air conditioner that form no part of the claimed design. The dot-dash broken lines represent boundaries of the enlarged portion and form no part of the claimed design.

1 Claim, 9 Drawing Sheets
